HIGH-VOLTAGE REGULATOR

John Priedigkeit, Oakland, Calif., assignor to the
United States of America as represented by the
United States Atomic Energy Commission

Application January 12, 1948, Serial No. 1,709

4 Claims. (Cl. 323—22)

1

This invention relates to a regulator circuit and more particularly to a high voltage regulator circuit the output polarity of which may be easily reversed.

Many types of regulator circuits have been developed; however, for certain types of electrical applications it is required to have a high voltage regulator which is stable over a large range of load conditions. To achieve this, the present invention has been devised employing radio frequency coupling in combination with an amplifier to control the operation of a regulator tube in opposition to fluctuations within the load circuit. Further, the invention has been designed so that a few minor changes in the circuit can be made to reverse the polarity of the regulator.

It is therefore an object of this invention to provide a new and improved high voltage regulator.

Another object of the invention is to provide a high voltage regulator having stable operation over a large range of load conditions.

A further object of this invention is to provide a radio frequency circuit coupled to an amplifier adapted to control the operation of a regulator tube circuit in a desired manner.

A still further object of this invention is to provide a high voltage regulator the output polarity of which is easily reversed.

Other objects and advantages of the invention will be apparent in the following description and claims considered together with the accompanying drawing, in which.

A schematic wiring diagram of the invention is the sole figure thereof.

Referring to the drawing in detail, there is shown a pentode type tube 11. The control grid of this tube 11 is connected to a grounded terminal 12 of a direct current source 13 through a resistor 14. The cathode of the tube 11 is connected to the second terminal 16 of the source 13. A by-pass condenser 17 is connected between the two terminals 12 and 16 of the source 13. Other connections of the tube 11 are: the suppressor grid is connected to the cathode through line 9, the screen grid is connected to the cathode through a by-pass condenser 18 and to a dropping resistor 19, and the anode is connected to a dropping resistor 21. The anode of the tube 11 is further connected to the third grid of a pentagrid mixer type tube 22. Other connections of the tube 22 are: the fifth grid is connected through line 8 to the cathode which is connected to the terminal 16 through a by-pass condenser 23, the fourth grid is connected to the second grid which is con-

nected to a dropping resistor 24, the first grid is connected to a coupling condenser 26 and to an inductance 27, and the anode is connected to an inductance 28. The condenser 26 is connected to the variable portion of a variable inductance 29 which is connected at one end to the anode of an oscillator tube 31 through a coupling condenser 32 and at the other end is connected to the terminal 16 through line 7. A variable condenser 33 is connected in parallel with the inductance 29. The anode of the tube 31 is connected to an inductance 34. The cathode of the tube is connected to the terminal 16. The control grid is connected to a resistor 36 which is in turn connected to the cathode. A series connected condenser 37 and inductance 38 are connected in parallel with the resistor 36. Also shown is a source 39 of direct current used to supply operating voltages to the tubes 11, 22, and 31. Five resistors 41, 42, 43, 44, and 46 form a voltage divider and are connected in series across the direct current source 39. The junction between the source 39 and the resistor 41 is connected to the terminal 16 through line 6. The junction of the resistors 41 and 42 is connected to the inductance 27. The common connection between the resistors 42 and 43 is connected to the resistor 19, to inductance 34 and to the cathode of the tube 22. The junction between the resistor 43 and 44 is connected to the resistor 21. A final connection of the voltage divider is made from the junction between the resistor 46 and the source 39 to the resistance 24 and the inductance 28. The anode of the tube 22 is also connected to a coupling condenser 47 which couples the output of the tube to a tank circuit comprising a parallel connected variable condenser 48 and inductance 49 which, in turn, is connected to the terminal 16.

An inductance 51 is placed in proximity with the inductance 49 so that there is an inductive transfer of energy between them. One end of this inductance 51 is connected to the junction between two resistors 52 and 53 of a resistance voltage divider and the other end is connected to the control grid of a pentode type amplifier tube 54 and to a variable condenser 56. A by-pass condenser 57 is connected between the junction of the resistors 52 and 53 and the condenser 56. There is also a common connection between the resistor 52, the condenser 56, and the condenser 57 and this junction is connected to the cathode of the tube 54 through line 5. Further connections of this tube 54 are: the suppressor grid is connected to the cathode through line 4,

the screen grid is connected to a by-pass condenser 58 and to the adjustable portion of a potentiometer 59, and the anode is connected to an inductance 61 and to a coupling condenser 62. The condenser 58 is further connected to the cathode of the tube 54. The coupling condenser 62 is connected to the cathode of a diode type detector tube 63 which is also connected to a tank circuit comprising a parallel connected variable condenser 64 and fixed inductance 66. The 10 anode of the tube 63 is connected to a resistor 67 and to the control grid of a triode type driver tube 68. The tubes 54, 63, and 68 are furnished operating voltages by a direct current source 69 and an alternating current source 71 in the following manner. The positive terminal 72 of the source 69 is connected to one side of the potentiometer 59, to the anode of the tube 68 through a dropping resistor 73, and to the anode of the tube 54 through the inductance 61. The neutral terminal 74 of the source 69 is connected to the other side of the potentiometer 59 and to the cathode of the tube 54. The terminals of the source 71 are connected to opposite ends of the primary winding of a transformer 76. This transformer 76 has two secondary windings 77 and 78, the former of which is center tapped. The end terminals of the secondary winding 77 are connected to the anode leads of a double diode rectifier type tube 79 and the end terminals of the other secondary winding 78 are connected to the heater type cathode of this tube. The center tap of the secondary winding 77 forms the negative terminal of a full wave rectified voltage, the positive side of which is taken from the cathode of the tube 79. This voltage is then filtered through a filter network comprising a condenser 81, an inductance 82, and a condenser 83. The output of the filter network is then connected across a bleeder resistor 84. The positive side of the voltage across this resistor 84 is then connected to the negative terminal 86 of the source 69, to the cathode of the tube 68, and to the resistor 53. The negative side of the voltage across the resistor 84 is connected to the resistor 67 and to the tank circuit comprising the variable condenser 64 and fixed inductance 66. The anode of the tube 68 is further connected to the control grid of a triode type regulator tube 87 and to the cathode of the tube 54 through a resistor 88. The cathode of the tube 87 is also connected to the cathode of the tube 54 and is further connected to a terminal 89. The anode of this tube 87 is connected to a terminal 91 and to a resistor 92 which is connected to the control grid of the tube 11.

Now consider the normal operation of the invention with the sources 13, 39, 69, and 71 properly energized and with no external connections made to the terminals 89 and 91. Under these circumstances there will be no current flowing through the tube 87 and therefore no voltage drop across the resistor 14 because of load voltage. The source 13 maintains the control grid of the tube 11 at a positive voltage with respect to the cathode and the tube will conduct at a maximum rate. The voltage of the anode of this tube 11 will be at a low positive value and will bias the third grid of the mixer tube 22 accordingly. The tube 31 and its associated circuits comprise a blocking oscillator which generates a radio frequency signal in the tank circuit of the anode. A portion of the radio frequency signal is impressed on the first grid of the tube 22. The out-

put of the tube 22 as developed in the tank circuit connected to the anode is then a radio frequency voltage, the magnitude of which is controlled both by the position of the take-off point on the inductance 29 and the input voltage from the anode of the tube 11. The radio frequency voltage is then inductively transferred between the inductances 49 and 51. Since the inductance 51 is a portion of a tank circuit in the control grid circuit of the amplifier tube 54, the radio frequency voltage is amplified through the tube. The radio frequency voltage at the anode of the tube 54 is impressed on the cathode of the detector diode tube 63 which is normally biased negatively through a tank circuit to increase its sensitivity. This tube 63 is so connected that it will conduct only during the time the cathode is more negative than the anode; therefore, the output voltage developed across the resistor 67 is unidirectional and biases the control grid of the tube 68 positively. The control grid of the tube 87 is connected to the anode of the tube 68 and therefore is positively biased. Thus the tube 87 will be conductive when connected in series with a device 93 to be regulated by means of the terminals 91 and 89, respectively.

When these latter connections have been made, current flows through the tube 87 and a voltage, equal to the voltage across the device 93 to be regulated, appears across the resistors 92 and 14. The voltage across the resistor 14, a portion of the total voltage, is thus negatively impressed on the control grid of the tube 11, causing the current flowing through the tube to decrease. The anode voltage of the tube 11 thereby increases and results in a more positive voltage being applied to the third grid of the tube 22. Thus, the amplitude of the radio frequency signal output of the tube 22 is increased. Since the output of the tube 22 is inductively coupled to the control grid of the tube 54, the increased radio frequency voltage is amplified and impressed on the cathode of the detector tube 63. This results in an increased positive rectified voltage being applied to the control grid of the driver tube 68. The tube 68 then conducts more heavily, resulting in a decrease of voltage at the anode. The voltage impressed at the control grid of the tube 87 is thereby decreased and the current flowing through the tube is reduced thereby. The foregoing describes the action of the circuit until the current flowing through the device 93 to be regulated adjusts the voltage across the device 93 until such voltage reaches an equilibrium value as determined by the value of the voltage of the source 13.

Now with the equilibrium value of the voltage across the device 93 to be regulated established, consider the effect of an increase in the voltage across the device 93 to be regulated. The action of the circuit will be similar to that outlined above for the initial connection of the device 93 to be regulated to the terminals 89 and 91; that is, the voltage drop across the resistor 14 increases and this voltage increase is translated through the circuit to decrease the bias of the control grid of the regulator tube 87, whereby the current flowing through the tube 87 is decreased until the voltage across the device 93 to be regulated is reduced to the equilibrium value.

A decrease in the value of the voltage across the device 93 to be regulated results in a decrease in the voltage drop across the resistor 14 and raises the bias of the control grid of the tube 11. The conductivity of the tube 11 is then increased

and the anode voltage is decreased. This voltage decrease is connected to the third grid of the tube 22 where it results in a decrease in the radio frequency output of the tube. Thus the radio frequency voltage inductively coupled to the control grid of the tube 54 is reduced. This means that the output of the detector tube 63 is less, thereby decreasing the bias of the tube 68. The anode voltage of the tube 62 is then increased because of the decreased conductivity of the tube. The control grid of the tube 87 is therefore biased more positively to increase the conductivity of the tube 87, whereby the voltage across the device 93 to be regulated is returned to the equilibrium value.

In order to reverse the polarity of the output the following changes and corrections must be made:

1. The regulator tube 87 is reversed so that the anode is connected to the terminal 89 and the cathode to the terminal 91.

2. The source 11 is removed from the circuit, thereby removing the negative bias applied to the control grid of the tube 68 and to the cathode of the tube 63.

3. The connections of the tube 63 are reversed.

4. The polarity of the source 13 is reversed so that the control grid of the tube 11 is normally biased negatively with respect to the cathode.

With these changes accomplished, a rise in the voltage across the device 93 to be regulated results in a positive signal being applied to the control grid of the tube 11 and consequently a negative signal to the third grid of the tube 22, thereby reducing the amplitude of the radio frequency output voltage of the tube 22. The reduced radio frequency voltage is inductively coupled to the control grid of the tube 54 where it is amplified and then impressed on the anode of the detector tube 63. Since the tube 63 is so connected that it conducts only during the time the anode is more positive than the cathode, a decreased rectified voltage is applied negatively to the control grid of the driver type tube 68. This tube 68 then conducts more heavily and decreases the positive control grid bias of the tube 87. Thus the conductance of the regulator tube 87 is decreased and the voltage across the device 93 to be regulated is returned to a predetermined equilibrium value.

Similarly, a reduction in the voltage across the device 93 to be regulated results in a decrease in the positive signal being applied to the control grid of the tube 11 and consequently a positive signal to the third grid of the tube 22, thereby increasing the amplitude of the radio frequency output of the tube 22. The increased radio frequency voltage is inductively coupled to the control grid of the tube 54 where it is amplified and impressed on the anode of the detector tube 63. Since the output voltage of the tube 63 is impressed on the control grid of the tube 68, this control grid becomes more negative and decreases the conductivity of the tube 68, thereby raising its anode voltage which is connected to the control grid of the regulator tube 87. The increase in the control grid bias of the tube 87 causes the tube to conduct more heavily, thereby restoring the value of the voltage across the device 93 to be regulated to the predetermined equilibrium value.

It is to be noted that the coupling between the inductances 49 and 51 can be accomplished by means of a condenser connected from the condenser 41 to the control grid of the tube 54. The primary requisite is to insulate the two sections

of the circuit from each other, since the section including the tubes 54, 63, 68, and 87 are at the high voltage of the load while the section including the tubes 11, 31, and 22 are at the relatively low voltage of the source 39.

While the salient features of this invention have been described with respect to one embodiment it will, of course, be apparent that numerous modifications may be made within the spirit and scope of this invention and it is therefore not desired to limit the invention to the exact details shown, except insofar as they may be defined in the following claims.

What is claimed is:

15. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a radio frequency amplifier having an input and an output, inductive transfer means connected between said controlling means and said radiofrequency amplifier input for establishing a predetermined output voltage, rectifier means connected to said radiofrequency amplifier output for converting said output voltage into a unidirectional voltage, means connected between said rectifier and regulator tube for establishing a predetermined positive bias for said regulator tube, and voltage divider means connected in parallel with said device to be regulated, a portion of said voltage divider being connected in said direct current amplifier input circuit.
20. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
25. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
30. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
35. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
40. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
45. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
50. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
55. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
60. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
65. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
70. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.
75. In a regulating circuit, the combination comprising a regulator tube in series with a device to be regulated, a direct current amplifier having an input and an output, a power supply source of unidirectional voltage connected to said amplifier input for establishing a predetermined output voltage, an oscillator for developing a high frequency voltage, means for controlling the amplitude of said high frequency voltage with said amplifier output voltage, a rectifier circuit, inductive means for coupling said high frequency voltage to said rectifier, means connecting the output of said rectifier circuit to said regulator tube, and means for impressing a fraction of the voltage across said device to be regulated upon the input to said direct current amplifier.

developed by adding a portion of said load voltage to the voltage of said source, an oscillator for developing a high frequency voltage, means for varying said high frequency voltage in response to said combined voltage at the output of 5 said amplifier to develop a modulated high frequency voltage, a second amplifier, means for coupling said modulated high frequency voltage to said second amplifier, a rectifier, means for connecting the output of said second amplifier to 10 said rectifier, and means for biasing said regulator tube with the output voltage of said rectifier.
